UNITED STATES PATENT OFFICE.

ERNEST H. W. BADEN, OF ST. JOSEPH, MISSOURI.

REINFORCEMENT FOR SHIRT-FRONTS.

1,125,440.

Specification of Letters Patent.

Patented Jan. 19, 1915.

Application filed August 17, 1910. Serial No. 577,601.

To all whom it may concern:

Be it known that I, ERNEST H. W. BADEN, a citizen of the United States, residing at the city of St. Joseph, in the county of Buchanan and State of Missouri, have invented certain new and useful Improvements in Reinforcements for Shirt-Fronts, of which the following is a specification, reference being had therein to the accompanying drawings.

In the old style shirts the part of the bosom that covers the clavicle of the wearer breaks long before the greatest material services have been obtained from the rest of the shirt.

It is the object of the present invention to provide a shirt in which this particular part of the bosom is reinforced, with the result that the life of the shirt is considerably longer than the life of the old style shirt.

In the accompanying drawings forming part of this specification, in which like numbers of reference denote like parts wherever they occur, Figure 1 is a front view of a shirt having its bosom reinforced adjacent the collar band; Fig. 2 is an inside elevation, on an enlarged scale, showing the reinforcement secured to part of the left half of the bosom; and Fig. 3 is an inside elevation, on an enlarged scale, showing the reinforcement secured to part of the right half of the bosom.

The two halves 1 and 2 of the bosom of the shirt 3 are secured along seams 4 and 5, respectively, to the yoke 6 and, also, along seam 7 to the collar band 8. A collar (not shown in the drawings) can be attached to collar band 8 by means of collar buttons or, if desired, same can be sewed to said band. The front edge 9 of half 1 is plaited and is stitched along seams 10 and 11. Button holes 12 are formed in the plaited edge 9 in order to attach said edge to buttons 13 on the adjacent hemmed edge 14 that is stitched along seams 15 and 16.

The reinforcement consists of two pieces or gussets 17 of plain woven material that are arranged to underlie the parts of halves 1 and 2, respectively, that cover the collar bone of the wearer. Each piece is cut with a configuration similar to a trapezium and

is arranged on the bias to its half 1 or 2. The longest edge 18 of said piece is preferably a selvage edge, the edges 19 and 20 adjacent thereto being cut on the bias and edge 21 opposite said selvage edge being curved to fit adjacent the collar band 8. The edges 19, 21, and 20 of one piece 17 are secured in seams 4, 7, and 10 to yoke 6, collar band 8, and the plaited edge 9, respectively, and the edges 19, 21, and 20 of the other piece 17 are secured in seams 5, 7, 15 and 16, to yoke 6, collar band 8 and the hemmed edge 14. Each edge 18 extends diagonally across the upper part of its respective half 1 or 2 and, as said edge is a smooth selvage edge, it is unnecessary to stitch same to the bosom of the shirt. The fact that the usual seams are utilized to hold the reinforcement in place obviates the necessity of providing extra stitching that would obviously show on the front of the shirt. By means of this reinforcement the part of the shirt below and around the front of the neck is greatly strengthened and is prevented from breaking for the reason that the stresses, to which said part of the shirt is subjected, are distributed to the pieces 17. The reinforcement greatly increases the strength of the collar band 8 and maintains the proper curve of same in front of the neck of the wearer.

I claim:

The combination with a negligée shirt or the like having a front opening, a yoke, and collar band of a reinforce located on the inside of the shirt extending from near the front opening to the edge of the yoke and base of the collar band, and stitched to said yoke and collar band and to the shirt near the front opening, with the lower edge of the reinforce which extends from near the front opening toward the yoke unsecured.

In testimony whereof I have hereunto affixed my signature in the presence of two witnesses.

ERNEST H. W. BADEN.
